UNITED STATES PATENT OFFICE.

CHARLES A. REEVES, OF ST. LOUIS, MISSOURI.

MECHANICAL MOVEMENT.

Application filed November 22, 1926. Serial No. 149,919.

My invention relates to devices for the transmission of energy and more particularly to that class of devices in which means such as flywheels are provided for meeting 5 temporarily power demands beyond the normal capacity of the power source.

My purpose is to produce a device wherein the planetation of a gear about the axis of a wheel on which it is peripherally mounted 10 results in the actuation of the immediate driving agent of an objective, the wheel to have peripheral weights through which gravity may contribute to the desired delivery result.

15 For accomplishing my purpose I offer a mechanism including in a preferred construction a wheel of spaced halves representing a comparatively large mass, the inertia of which is to be overcome, and its rotation established, by a comparatively small force, exercised over a relatively long period as well known means may suggest; the said wheel to be provided with weights suspended from and keyed to spindles rotatably 20 mounted peripherally between the halves, the spindles projecting beyond the surface of one of said halves, the projecting ends carrying and keyed to planetating gears; the planetation of said gears effecting their rotation with reference to the axis of the wheel, and said rotation actuating reciprocatory 25 mechanism for the transmission of energy to an air compressor from which air is conveyed through suitable channels to a machine to be operated.

30 While many incidental results may be obtained from my arrangement, by additions thereto or by adjustments of gearings, I desire to include such variations of application 35 within the scope of my invention, as being suggested to mechanical ingenuity on the basis of the structure that I particularly claim and disclose in the accompanying drawing, in which the single figure is a perspective view of a rotor embodying my invention and actuated by power applied to its periphery.

Referring in detail to the drawing:

1 designates a wheel comprising a hub 2 40 rotatably mounted in bearings 3 of a frame 5; and spaced disks which will be referred to as a source disk 5 to which actuating energy is applied, and delivery disk 6 from which energy is delivered to the objective.

Each disk comprises respectively spokes 7 55 and 8 and peripheral sections or rims 9 and 10. Rotatably mounted in aligned bearing openings 11 and 12 in the peripheral sections 9 and 10 of the disks are a plurality of spindles 13, the spindles projecting beyond 60 the outside vertical surface of the delivery disk 6 to constitute shafts 14 on which planetating driving gears 15 are mounted and to which said gears are keyed.

Weights 16 depend from the spindles, suspended therefrom and held in permanent relation thereto by rods 17 which are secured to the spindles.

Internal annular gear 18 is provided for the rim 9 of source disk 5 of the wheel, in 70 the illustrated mode of actuating the device, power being applied through a pinion 19 connected with a power source not shown.

In operation, the application of energy 75 to the annular gear 18 causes rotation of the wheel and the revolution of the spindles, the suspended weights, and the driving gears, around the axis of the wheel. Such revolution, however, becomes planetation for the peripherally supported members mentioned, and is accompanied by peculiar rotational conduct due to construction and adjustment. The influence of the weights suspended from the spindles causes the spindles, and the driving gears locked on the projecting ends 80 of the spindles, to planetate, without individual rotation with reference to a fixed plane, around the wheel axis and hub. The spindles are permitted to execute revolution 85 in such manner by reason of their rotatable mounting in the bearing openings of the disks 5 and 6; and the spindles are compelled to retain their non-rotating relation to a fixed plane because of the restraint 90 against rotation exerted by the depending weights. The driving gears 15 are compelled to similar conduct as to rotation, through their locked engagement with the 95 spindles.

100 Although, in the revolution described, neither spindles nor driving gears have rotated with respect to their own axes or with respect to a fixed plane, both the gears and the spindles have rotated with respect to the axis, and the hub, of the wheel. Such 105 rotational conduct of the driving gears and of the spindles in relation to the hub of the wheel will be referred to as the effectual ro-

tation of these members, since their relative rotational process is a factor in producing an effect that is contemplated.

The effectual rotation of the driving gears 15 provides a step in the delivery of power to an objective. Further steps in such delivery will now be described, as they are represented in the drawing, and illustrative of transmission of energy to an objective in a device of this character.

Rotatably mounted on the spokes 8 of the delivery disk 6 are driven gears 20 meshed with the driving gears 15 and provided with crank pins 21 to which are connected reciprocating rods 22 driving pistons 23 of pumps 24, which may be air compressors mounted on the spokes 8 of the delivery disk 6.

The gear ratios of gears 15 and driven gears 20 are such that the effectual rotation of the driving gears 15 produces for example, five rotations of the gears 20 and five cycles of propulsion and withdrawal of the pistons 23. Each group comprised of driving gear, driven gear and pump operates independently; but all act synchronously. The pumps deliver the medium into channels 25 in the axle and conduct it to the objective in a suitable manner.

An increase of demand, for example an overload on the driven machine or objective, reacts upon the air compressor and upon the driving gears, retarding the driving gears in their effectual rotation, that is to say, preventing the driving gears from maintaining their normal position relative to the disk 6.

Retardation is extended through the driving gears to the spindles to which the said gears are keyed; and the spindles, rotatable in their bearings, tend actually to rotate on their own axes under such influence. The result is to cause the projection of the suspended weights outside of their normal circle of travel about the axis of the wheel. The suspensory rods 17 may be considered as lever arms carrying weights; the projection of such weights by the lever arms outside of their normal radius increasing the leverage influence of said weights. The weights therefore will exercise a larger levering influence than previously upon the driving gears towards retaining said driving gears in effectually rotating position.

Assuming energy being applied to the device through the annular gear, and the rotation of the wheel, and the effectual rotation of the driving gears in their revolutions, then the weights become the effectual means of transmitting energy to the air compressors. That is to say, the gravitational force exercised by the weights restrains the driving gears from rotation on their own axes and therefore compels said driving gears to effectual rotation with respect to the axis of the wheel—and so compels the driving gears to perform their work of actuating the air-

compressors. A surge of resistance will cause the driven gears to react extensively against the driving gears, and the driving gears will cause the supporting spindles to rotate and swing the weights into laterally extended position where they exercise leverage on the spindles and driving gears to actuate the driven gears.

The mass of the weights, and the source power applied, may be adjusted to the delivery requirements.

What I claim and desire to secure by Letters Patent is:

1. In a mechanical movement, a wheel comprising spaced halves, spindles rotatably mounted between the halves and adjacent their periphery, and spacing the halves, gears fixed to similarly projecting ends of such spindles and engaged with the actuating gearing of an objective, the spindles having depending arms, weights attached to the depending arms, and means for rotating said wheel.

2. In a mechanical movement, a wheel comprising spaced halves, axles transversely and rotatably mounted in the periphery of the halves, gears keyed to the said axles, weights suspended from the axles, and means for engaging said gears with the machine to be operated, the said weights being adjusted to tend to retain a diameter of a gear perpendicular, and return such gear to condition of perpendicularity of said diameter.

3. In a mechanical movement, a wheel comprising spaced halves, axles transversely and rotatably mounted in the periphery of the halves, spur gears keyed to the said axles, weights suspended from the axles, the weights restraining the axles for rotation of the same with respect to the wheel upon planetation of the axles about the wheel axis, transmission means engaged with said gears, said weights being extended from normal planetation by the reverse influence of the spur gears as retarded by a surge resistance from the power user for the purpose of balancing abnormal strain upon the source of power.

4. In a mechanical movement, a wheel comprising spaced halves, axles transversely and rotatably mounted in the periphery of the halves, pinions keyed to the said axles, weights suspended from the axles, the weights restraining the axles from rotation on their axes upon revolution about the wheel axis, a transmission geared with said pinions to a machine to be operated, said weights extended from normal planetation by the excess resistance from the delivery.

5. A power transmitting mechanism comprising a rotor, spindles carried at the periphery of the rotor, spur gears fixed to the spindles, weights suspended from the spindles to normally retain said spur gears in a

fixed attitude during rotation of the rotor, gears on the rotor and in connection with said first named gears, motors carried on the rotor, a means connecting the motors to the last named gears.

6. A power transmitting mechanism, comprising a rotor, spindles carried by the rotor, gears fixed axially on the spindles, weights

on the spindles to normally retain the gears from rotation, gears in mesh with the first named gears, and means for transmitting motion from the last named gears to an objective.

In testimony whereof I affix my signature.

CHARLES A. REEVES.
